UNITED STATES PATENT OFFICE

DANIEL D. GITT, OF AHRENDTSVILLE, PENNSYLVANIA.

FIFTH-WHEEL COUPLING FOR VEHICLES.

SPECIFICATION forming part of Letters Patent No. 239,042, dated March 22, 1881.

Application filed January 24, 1881. (No model.)

To all whom it may concern:

Be it known that I, DANIEL D. GITT, of Ahrendtsville, in the county of Adams and State of Pennsylvania, have invented certain new and useful Improvements in Combined Coupling and Fifth-Wheel; and I do hereby declare the following to be a full, clear, and exact description of the invention, such as will enable others skilled in the art to which it pertains to make and use it, reference being had to the accompanying drawings, which form part of this specification.

My invention relates to an improvement in combined couplings and fifth-wheels; and it consists, first, in casting the lower part of the fifth-wheel in a single piece with a socket for the coupling which is attached to the reach, whereby the usual king-bolt is dispensed with and a much stronger, cheaper, and more durable fastening is produced; second, in forming a projection upon the casting which forms both the lower part of the fifth-wheel and the socket, and pivoting the upper part of the fifth-wheel upon this projection, as will be more fully described hereinafter.

The object of my invention is to do away with the usual king-bolt, and to form a coupling for the reach which will allow either one of the axles to twist or turn without bringing any strain upon the fifth-wheel or any other part of the vehicle.

Figure 1 is a side elevation of my invention complete. Fig. 2 is a perspective of the casting which forms both the socket and the lower part of the fifth-wheel. Fig. 3 is a vertical section of my invention.

A represents the axle; B, the clip; and C, the casting, which is fastened to the axle by means of the clip, as shown in Fig. 3. This casting, as will be seen, forms both the lower parts, D, of the fifth-wheel and the socket for the coupling F, which is to be fastened to the reach in any suitable manner. That part of the casting which forms the fifth-wheel rests solidly upon the axle; but all of that part of the casting which forms the socket extends down below the top of the axle, so as to be in a direct line with the reach as it extends forward from the rear axle. In addition to the clip, by means of which this casting C is secured to the axle, the casting is provided with the ears G, through which screws are passed

into the axle so as to assist in holding the casting rigidly in place.

Extending horizontally through the casting, 55 on a level with the center of the axle, is an opening, the front part of which forms a socket for the ball I, which is formed upon the front end of the coupling F, while the rear part of the opening is not as deep as the front part, 60 but is made sufficiently wide to allow the coupling to play freely back and forth from side to side. The coupling having the ball upon its front end is passed through the casting from the front side, so that the ball will catch in the 65 socket that is made for it and the coupling extend through the rear part of the casting, and then the casting is secured to the axle by means of both clip and screws, as shown.

The great advantage in the use of the ball-and-socket joint, as here shown, consists in the fact that either one of the axles may get out of line with the other without bringing the slightest strain to bear upon the fifth-wheel or coupling, which is not the case where the usual 75 king-bolt is employed.

By the use of a ball-and-socket joint, as here shown, either the front or the rear portion of the vehicle may twist or turn to any desired extent without bringing the slightest strain to 80 bear upon the other axle, thus making not only a better coupling but a much stronger, cheaper, more durable, and safer one. King-bolts are always more or less liable to be broken when the front wheels run down into ruts or any 85 other sudden strain is brought to bear upon them; but where a ball-and-socket joint such as is here shown is used no strain of any kind can ever affect the vehicle in the slightest respect, and hence the vehicle is always safer 90 and stronger.

Upon the top of the casting C, at any suitable distance in the rear of the axle, is formed a circular projection, O, of any suitable size, and which forms the pivot upon which the upper portion, P, of the fifth-wheel turns.

Upon the top of the upper portion of the fifth-wheel is placed the washer Q, and down through this washer into the projection is passed a fastening-bolt, R. As the projection is long enough to extend slightly above the top of the upper portion of the fifth-wheel this washer bears directly upon the top of the projection, so that no matter how tightly the

washer may be clamped in position by means of the screw it will not in any manner affect the fifth-wheel itself. Through this upper part of the fifth-wheel will be formed any suitable openings for securing the springs or other suitable fastenings of the buggy to it.

It is my intention to use in connection with this coupling a compound zigzag spring which will allow the body of the vehicle to turn and 1c twist with much greater freedom than the usual elliptic springs will do, and hence the strain will be very greatly lessened upon the coupling and the body have a much easier and more pleasant riding movement.

15 Having thus described my invention, I claim—

1. The casting C D O, provided with a socket to receive the front end of the coupling F, in

combination with the clip B and the upper part of the fifth-wheel, substantially as shown. 20

2. In a coupling for vehicles, a casting having a horizontal opening through it, the front part of the opening forming a socket and the rear part of the opening being widened out so as to allow the coupling a lateral play, in combination with a coupling having a ball formed upon its front end, and which fits in the socket in the casting, substantially as specified. 25

In testimony that I claim the foregoing I have hereunto set my hand this 20th day of 30 January, 1881.

DANIEL D. GITT.
